UNITED STATES PATENT OFFICE.

MOSES G. FARMER, OF NEW YORK, N. Y.

EXERCISING-MACHINE.

SPECIFICATION forming part of Letters Patent No. 319,686, dated June 9, 1885.

Application filed October 14, 1884. (No model.)

To all whom it may concern:

Be it known that I, MOSES G. FARMER, a citizen of the United States, residing in New York, in the county and State of New York, have invented certain new and useful Improvements in Exercising-Machines, of which the following is a specification.

My invention relates to a class of apparatus employed for exercising the muscles, especially those of the arms and back, and the object of the invention is to provide a convenient device for indoor exercise.

The invention consists in constructing an apparatus in substantially the following manner:

Upon a suitable stationary frame there is carried a pivoted arm provided with a suitable handle, designed to extend horizontally above the head of the person using the apparatus and within reach of the outstretched hands. This handle and its supporting arm or crank are so constructed that the arms may be thrown forward, carrying the handle downward with it. It is desired, however, that the handle shall offer a certain amount of resistance to this movement, and for this purpose a balance-wheel is placed in the lower portion of the machine, and coupled with the axis of the arm or crank by means of suitable mechanical connections which, when the arm or crank is moved downward, cause the balance-wheel to be revolved against the force of suitable yielding springs which are placed under increased tension as the wheel is revolved by the forward movement of the arm and handle. When the handle is released, however, the springs tend to return the wheel to its normal position, again elevating the handle and arm.

The apparatus is provided also with a suitable rest for the back and shoulders of the person exercising, and this rest is rendered adjustable in a convenient manner.

In the accompanying drawings, Figure 1 is a front elevation of an exercising-machine embodying the features of my invention. Fig. 2 is a side view of the same; and Fig. 3 is a plan view of the machine.

Referring to the figures, A represents a suitable base, which is preferably supported upon three supports, a' , a'' , and a''' . Two standards, B' and B'' , extend from the base A vertically,

and between the upper ends of the same there is carried an arbor or shaft, C, upon which is carried a suitable arm or crank, D. At the extremity of the arm or crank D there is placed a handle, d, extending laterally a sufficient distance to allow the person employing the machine to stand beneath it and to grasp it with both hands.

It is designed that when the apparatus is in its normal position the arm D shall extend upward at an angle, and the handle d shall be at such a height that the person exercising may grasp it with arms outstretched. The arm D is so pivoted, by means of its arbor C, that it may turn downward in the direction indicated by the arrow.

For the purpose of affording a resistance to the movements of the same, and thereby securing the required amount of exercise for the operator, a balance-wheel, E, is supported upon a suitable shaft, e, between the lower portions of the uprights B' and B'' . Upon the axis e of the wheel E there are carried two drums, f' and f'' , which are designed to receive the cords e^3 and e^4 , respectively. These cords extend from corresponding drums or pulley-wheels, e^5 and e^6 , which are carried upon the shaft or arbor C. One of the cords e^3 , however, is so applied that when the handle is in its normal position it is wound a suitable number of times about the drum f' in such a manner that when the handle d is thrown downward it will be wound upon the drum e^5 , and will cause the wheel E to revolve in the direction indicated by the arrow. The cord d^4 , however, is so applied to the pulleys f'' and e^6 that the same movement of the handle d and wheel E will cause the cord to be wound upon the pulley f'' and unwound from the pulley e^6 . When, however, the handle d is moved upward, the direction of movement of the wheel E will be reversed, and likewise the cord e^3 will be wound upon the pulley f' and the cord e^4 will be wound upon the pulley e^6 .

For the purpose of relieving the cords from any sudden tension which might be sufficient to break them, suitable spiral or coil springs, g' and g'' , may be inserted in the lengths of each of the cords, as shown.

For the purpose of assisting in returning the wheel E and thus the handle d to their normal

positions, suitable cords, h' and h^2 , having springs f^3 and f^4 , are employed. These cords are each secured at one end to the arbor e and at their remaining ends to the respective 5 springs, and the remaining ends of the springs are respectively secured to the supports B' and B^2 . When the wheel E is revolved by the downward movement of the handle d , the cords h' and h^2 will be wound and the springs 10 f^3 and f^4 will be placed under tension. The tension of the springs serves to return the wheel to its normal position when the handle is released.

For the purpose of affording a support to 15 the back of the operator, a suitable rest, k , is employed. The rest is preferably cylindrical in form, and is carried upon an adjustable arm, k' , and normally stands in a position slightly below the axial line of the arbor C . 20 The arm k' , however, is secured to an extension, K , of the upright B' by means of a set-screw, k^2 , and nut k^3 , extending through the slot k^4 , formed in the extension K . By means of this set-screw and nut the rest may be adjusted not only toward and away from the 25 front of the machine, but its vertical position may also be adjusted by turning the arm k' upon the bolt or screw k^2 as a center. The handle d is also preferably adjustable in a like 30 manner in the arm or crank D .

I claim as my invention—

1. In an exercising-machine, the combination, substantially as hereinbefore set forth, of an arm or crank, its axis, a balance-wheel, 35 its axis, and a cord connecting the axis of said arm or crank with the axis of said balance-wheel, and serving to cause said wheel to revolve in a given direction when said arm or crank is moved in one direction, substantially 40 as described.

2. In an exercising-machine, the combination, substantially as hereinbefore set forth, of a pivoted arm or crank, an axis for the same, a handle extending in a direction par-

allel to said axis, with a balance-wheel, and 45 two cords or bands winding upon the respective axes in opposite directions, substantially as described, whereby said balance-wheel is caused to revolve in one direction when said arm or crank is moved in a given direction, 50 and in the opposite direction when said arm or crank is moved in the other direction.

3. In an exercising-machine, the combination, substantially as hereinbefore set forth, with the handle d , the arm D , and the axis C , 55 of the balance-wheel E , the cords e^a and e^b , with their respective pulleys, and the spring tending to normally retain said wheel in a given position, substantially as described.

4. In an exercising-machine, the combination, substantially as hereinbefore set forth, of a crank, an axis upon which said crank is carried, a handle for turning said crank upon its axis, with a balance-wheel, two cords or bands winding upon the respective axes in 60 opposite directions, whereby said balance-wheel is turned in one direction or the other accordingly as said crank is moved in one direction or the opposite, an adjustable support or rest, an arm carrying the same, a support 70 for said arms, and means, substantially such as described, for securing said arm to said support in any required position.

5. The combination, substantially as hereinbefore set forth, with the arm D , the handle 75 d , the wheel E , and the connections between the same, substantially such as described, of the rest k , the arm k' , the extension K , having the slot k^4 , and the set-screw and nut for uniting the last-named arm with said extension. 80

In testimony whereof I have hereunto subscribed my name this 26th day of August, A.D. 1884.

MOSES G. FARMER.
